MILK BOTTLE CASE AND BOTTOM FRAMES
THEREFOR

John F. Maurer, Leonia, N.J.

Application March 15, 1950, Serial No. 149,763

1 Claim. (Cl. 217—69)

1

This invention relates to milk bottle cases and the like and has particular reference to a metal frame for protecting and reinforcing the bottom edges thereof so as to retain the rectangular formation of the cases and prevent spreading of the side and end walls thereof in order that the cases may be transported on traveling conveyors during the filling and cleaning operations without interference.

An object of the invention is to provide a metal frame composed of two mating sections arranged with the inner ends thereof disposed in overlapping secured relation so as to form a complete rectangular frame.

The invention also resides in a method of producing a metal frame of said character consisting in forming mating frame sections from flat strips of material by cutting the same to provide recesses at longitudinally spaced locations, stamping the flat strips into channel-shaped formation and bending the same into U-shaped formation.

It has been the practice to form rectangular bottom frames for milk bottle cases by stamping the frames from sheets of metal. This requires the use of metal sheets of high quality and of a size somewhat larger than the length and width of the cases. In producing the rectangular frames in this manner, the central portions of the sheets are cut out and must be used for other purposes so as to reduce the cost of manufacture and eliminate waste. In order to overcome the objections to producing the rectangular frames from large sheets of material and yet provide a frame which has all the benefits of an integral frame, the present invention comprehends the manufacture of mating frame sections from narrow lengths of material which sections are formed in straight lengths and then bent to U-shaped formation as the same are secured over the bottom edges of the cases. In producing the frame sections in straight lengths, the same are formed into U-shaped formation in cross-section and are cut away or recessed at longitudinally spaced locations to permit bending of the straight lengths where the sections engage about the corners of the cases. Constructing the metal frames in this manner facilitates the manufacture thereof, eliminates waste and the need of handling large sheets of material and provides frame sections which can be readily affixed to milk bottle cases and the like.

With the foregoing and other objects in view, reference is now made to the following specification and accompanying drawings in which the preferred embodiment of the invention is illustrated.

2

In the drawings:

Fig. 1 is an underside view of a milk bottle case provided with a bottom frame constructed in accordance with the invention.

Fig. 2 is a perspective view of the frame sections shown in separated juxtaposition and with one of the corner elements shown in position on each of the sections.

Fig. 3 is an enlarged fragmentary cross-sectional view taken approximately on line 3—3 of Fig. 1, as the same would appear with the case shown with the top uppermost.

Fig. 4 is an enlarged fragmentary cross-sectional view taken approximately on line 4—4 of Fig. 5.

Fig. 5 is a cross-sectional view taken approximately on line 5—5 of Fig. 1.

Fig. 6 is a fragmentary view similar to Fig. 5 but showing a modified construction of bottom member connecting the frame sections together.

Fig. 7 is an enlarged fragmentary sectional view taken approximately on line 7—7 of Fig. 6.

Fig. 8 is a perspective view of a metal strip from which each of the frame sections are produced.

Fig. 9 is a fragmentary view of one of the frame sections in straight length as produced from the metal strip shown in Fig. 8.

In the embodiment of the invention illustrated in the drawings, a milk bottle case A of the slatted wooden type is shown, which includes end and side walls B and C and inner and outer angulated corner elements 10 and 11 between which the ends of the wooden slats are secured by means of wires or rods 12 which extend downwardly between the inner corner elements 10 and the inner ends of loops 13 formed integrally with the outer corner elements 11 and projecting through slots 14 in the inner corner elements. The outer corner elements 11 are also formed with inwardly directed beads 18 which engage in vertical slots 19 in the outer faces of the slats while the upper and lower ends of the outer corner elements 11 are formed with inwardly directed overlapping apertured extensions 20 through which the wires or rods 12 also extend.

In order to provide a channeled reinforcement for the bottom edges of the end and side walls B and C of the case which has all the benefits of an integral frame, two mating frame sections 21 and 22 are fashioned from flat strips of metal D, as illustrated in Fig. 8 of the drawings, which are cut and stamped to form an angulated strip of U-shaped formation in cross-section including an outer flange 23, an inner flange 24 of relatively lesser height than the outer flange 23, and

a horizontal bight portion 25 connecting the said flanges, as illustrated in Fig. 9 of the drawings. The said strip is cut and recessed at longitudinally spaced points to provide confronting tongues 26 in the outer flange 23 and with the inner flange 24 and the bight portion 25 formed with longitudinally spaced inwardly extending recesses 27 located in alignment with the recesses between the confronting tongues 26.

The frame sections 21 and 22 are also provided with apertured ears 29 and 30 on the ends of the outer flanges 23 thereof respectively, the ears 29 being provided with inwardly directed tubular bosses 31 respectively, while the apertured ears 30 are offset inwardly from the plane of the flanges 23 respectively. The sections are bent into U-shaped formation in plan and are secured together in end to end relation to form a complete rectangular frame by engaging the apertured ears 30 on the bosses 31 of the ears 29 and flattening or peening the inner ends of the bosses against the inner faces of the ears 30. The frame is then applied to the bottom edges of the case with the tongues 26 located at the corners thereof and the connections between the sections being located intermediate the longitudinal sides B of the case.

In bending the straight frame sections into U-shaped formation, as shown in Fig. 2, the side edges forming the recesses 27 are brought together to form right angle bends with the tongues 26 projecting outwardly at right angles to each other at each of the corners. The outer flanges 23 of the sections project over the outer faces of the side and end walls while the inner flanges 24 project over the inner faces thereof and the bight portion 25 overlies the bottom edges of said side and end walls. The tongues 26 extend into the outer corner pieces 11 while the upper apertured extensions 20 overlie the upper edges at the corners of the case. The lower extensions 28 protrude through slots in the outer flanges 23 formed by the tongues 26 and through the lowermost slots 14 in the inner corner elements 10 with the wires or rods 12 engaging through the openings in said extensions as hereinbefore described.

The sections 21 and 22 are secured to the walls of the case by longitudinally extending rods 34 which form supports for the milk bottles. A transversely extending cross member 35 having downwardly directed inner ends 36 is arranged between the side walls B and secured thereto by

rivets 37 which extend through the side wall B and through the apertured ears 29 and 30 for securing the ends of the sections 21 and 22 together and to the side walls.

5 Instead of the cross member 35 shown in Figs. 1, 3 and 5 of the drawings, a cross bar 39 may be employed which underlies the longitudinally extending rods 34 and extends through the side walls B of the bottle case A and through the apertured ears 29 and 30 with the outer ends of said bar riveted over as at 40 against the outer faces of said apertured ears for securing the ends of the sections 21 and 22 together and to the side walls.

15 What is claimed is:

A metal frame for a wooden bottle case consisting of two mating sections each of U-shaped formation in plan and of channel-shaped formation in cross-section having inner and outer flanges and a bight portion connecting said flanges, said sections having apertured ears in said outer flanges at the ends thereof arranged with the ears in one section disposed in overlapping relation with the ears in the other section and one of the ears of each section having a tubular extension engaging through an apertured ear of the other section and riveted thereto, said sections engaging over the bottom edges of the wooden case with the inner and outer flanges projecting over the inner and outer faces of the side and end walls of the case respectively and the bight portion overlying the bottom edge of the case, a cross brace disposed between the overlapping ends of said sections, and rivets extending through said overlapped ears and said tubular extensions and the ends of said brace for securing the sections and the cross brace to the wooden case.

JOHN F. MAURER.
